ROAD BARRICADE

Robert S. Wolf, 9 Leonard J. Kalish, Suite 1629,
Du Pont Bldg., Miami 32, Fla.
Filed Dec. 28, 1962, Ser. No. 247,934
9 Claims. (Cl. 256—64)

This invention relates to a novel road barricade.

The primary object of the invention is the provision of a simpler, more efficient, and more easily and quickly set up device of the kind indicated, which eliminates the need for the loosening and tightening of bolts or other fastenings when setting up the device.

Another object of the invention is the provision of an inexpensive and long lasting device of the character indicated above, which comprises at least one and usually a pair of standards and any desired barricade bar, the standards consisting of single, generally vertical rods or bars having low-profile ground-engaging feet, on their lower ends, which, because of their low profiles are not subject to being damaged by the bumper bars of vehicles, and which can be run over by the tires of vehicle wheels, without necessary damage thereto. Present barricades use A frame standards whose upwardly converging straight legs present obstacles likely to be struck and damaged by vehicle bumper bars and the like, when vehicles come close to the barricades, as when the barricades are set up parallel to a road, as one side of the road is being repaired and its other side is open to traffic.

A further object of the invention is the provision of a device of the character indicated above wherein the bars or rods of the standards have vertically spaced, pivoted clips, of simple and inexpensive design, which are spaced from each other at a distance greater than the width of a barricade bar, the barricade bar being adapted to be placed freely between the clips with the standards in erect perpendicular positions, and the standards then tilted inwardly toward each other, whereby the distances between the clips are reduced and the clips are forced into secure retaining or clamping engagements with the upper and lower edges of the barricade bar, and at the same time the over-all height of the barricade is reduced to the desired height from the erect heights of the standards.

A still further object of the invention is the provision of an economical and easily serviced device of the character described above, wherein the rods or bars of the standards are provided with at least three vertically spaced bolt holes, so that the clips can be spaced at different distances from each other, by inserting their bolts through the appropriate holes, for the accommodation of barricade bars of different widths, and wherein, in case of damage to clips, bolts, or standard feet, these can be readily individually replaced from stock, instead of having to go to the expense of replacing the entire standards, as is now the practice; and wherein the clips are adapted to be reversed for accommodating barricade bars of different thicknesses; and wherein, in case of damaged standards, their undamaged components may be saved to make up other complete standards economically, so as to eliminate the expense of providing new standards.

Other important objects and advantageous features of the invention will be apparent from the following description and the accompanying drawings, wherein, for purposes of illustration only, a specific form of the invention is set forth in detail.

In the drawings:

FIGURE 1 is a perspective view of a barricade in accordance with the present invention;

FIGURE 2 is an enlarged fragmentary front elevation of a portion of the barricade of FIGURE 1;

FIGURE 3 is a vertical transverse section taken on the line 3—3 of FIGURE 2;

2

FIGURE 4 is a fragmentary schematic and diagrammatic front elevation, showing the reduction in the spacing of the clips, as a standard is tilted out of erect position, which produces clamping of the clips on the upper and lower edges of the barricade bar;

FIGURE 5 is an enlarged exploded perspective view of a clip and its bolt;

FIGURE 6 is a view like FIGURE 3, showing the clips reversed for accommodating a barricade bar which is narrower and thicker than the barricade bar of FIGURE 3.

Referring in detail to the drawings, wherein like numerals designate like parts throughout the several views, the illustrated barricade comprises a pair of similar standards 10, and a horizontal barricade bar or slab 12 supported thereon.

Each of the standards 10 comprises a straight, generally vertically elongated rod or bar 14, herein shown as being tubular and made of metal, such as galvanized steel. 20 However, rods or bars of any other forms and material are contemplated by the present invention. The rods 14 have upper ends 16 and are formed at their lower ends with flat arcuate saddles 18, which embrace one side of the middle of the horizontal cross members 20 of low profile inverted U-shaped ground-engaging feet 22, and are removably secured in place by means of bolts 24 extending through the saddles and the cross members 20, so that a foot 22 can be readily replaced.

The standard rods 14 are provided, adjacent to their upper ends, with vertically spaced upper, intermediate, and lower bolt holes 26, 28 and 30, respectively. Additional bolt holes may be provided, if desired. In the arrangement shown in FIGURES 1 to 3, wherein the barricade bar 12 is relatively wide and relatively thin, upper and lower pivot bolts 32 and 34 are inserted through the upper hole 26 and the lower hole 30, for pivotally supporting similar but reversed upper and lower clips, or hook elements 36 and 38, respectively.

Each of the clips comprises a relatively narrow web 40, adapted to have free bearing against one side of the standard rod 14, and having a centered hole 42 through which the shank 44 of the related pivot bolt is passed, the shank having a fixed head 46 engaged with the outer side of the web 40, in opposition to a self-locking nut 48, on the other end of the shank 44, which bears freely against the other side of the standard rod.

Parallel, spaced, horizontal arms 50, 54, extend laterally outwardly from the upper and lower ends of the web 40 and are spaced at such a distance that these arms engage opposed upper and lower, edge faces of the bolt head 46, as shown in FIGURE 2, whereby the bolt is prevented from rotating as the nut 48 is applied to the bolt shank, thereby eliminating the need to use two wrenches, when installing the clips or reversing the same.

55 The arms consist of flat, relatively long arms 50, having lateral transverse flanges 52, on their outer ends, which extend away from flat, relatively short arms 54, which have lateral transverse flanges 56, on their free ends, which extend away from the upper arms 50. As shown in FIGURE 3, the short arms 54 are the inner arms and are used for supporting a relatively wide and thin barricade bar 12, whereas, as shown in FIGURE 6, the clips are reversed, by rotating them on the bolts, in addition to placing the lower bolt in the intermediate bolt hole 28, and 60 the long arms 50 used for supporting a relatively narrow and thick barricade bar 12.

The standards 10 are longer than or taller than the contemplated height of the completed and set-up barricade, and the clips are spaced from each other, at distances 70 greater than the width of the associated barricade bar, so that, as shown, at the right-hand side of FIGURE 4, the barricade bar can be readily passed between the upper and

lower clips 36 and 38, with the standard 10 in erect position; and so that when the standard is tilted inwardly, toward the other standard, as shown, at the left-hand side of FIGURE 4, the effective distance between the upper and lower clips is reduced, while the clips pivot on their bolts, and make clamping contacts with the upper and lower edges of the barricade bar, the height of the barricade being thus reduced to the desired value, with the feet 22 of the standards 10 located at the outer ends of the barrier bar 12.

When it is desired to transport or store the barricade, in compact condition, it is a simple and quick operation to erect the standards 10, remove the barricade bar 12 from between the clips, and lay the standards along the barrier bar. Replacement of damaged clips is done simply by backing off the nuts 48 on the associated pivot bolts. Replacement of a foot 22 is simply a matter of loosening the bolt 24.

In addition to serving as a barricade, the assembly of FIGURE 1 may be grouped in multiples of at least two and in that way provide a frame for supporting planks, staging or the like.

It is to be noted that it is often the practice with present barricades, where such as a repair spot on a roadway or the like is to be guarded against traffic, to use a barricade which involves only the barricade bar and a single standard, with one end of the bar resting upon the surface and the other end thereof supported on the single standard. The components of the above described barricade are adapted to be used in the same way, for the same purpose.

Although there has been shown and described a preferred form of the invention, it is to be understood that the invention is not necessarily confined thereto, and that any change or changes in the structure of and in the relative arrangements of components thereof are contemplated as being within the scope of the invention as defined by the claims appended hereto.

What is claimed is:

1. A road barricade comprising a pair of standards, 40 and a horizontal barricade bar extending between and supported on the standards, said standards having pairs of upper and lower clips thereon which in erect positions of the standards are spaced from each other at distances greater than the width of the barricade bar, said bar having upper and lower edges, the standards being tilted toward each other whereby the distances between the upper and lower clips are reduced and the upper clips engage the upper edge of the barricade bar and the lower clips engage the lower edge of the barricade bar, said standards having vertically spaced upper, lower, and intermediate bolt holes, and upper and lower pivot bolts carrying the upper and lower clips, the upper pivot bolt being engaged through the upper bolt hole and the lower pivot bolt being engaged selectively through the intermediate or the lower bolt hole to space the clips for accommodating barricade bars of different widths, each of said clips comprising a web bearing against one side of the standard and having a centered hole through which a related pivot bolt passes, the related bolt having a head engaged with the outer side of the web and a nut bearing against the other side of the standard, the web having laterally, outwardly extending, horizontal, parallel, spaced upper and lower arms on its upper and lower ends, respectively, which have oppositely and outwardly directed lateral flanges on their free ends, the arms being non-rotatably engaged with opposed edge faces of the pivot bolt heads, the upper arms being longer than the lower arms, the clips being rotatably reversible on the pivot bolts for positioning the shorter arms in engagement with the upper

and lower edges of a relatively thin barricade bar and for positioning the longer arms in engagement with the upper and lower edges of a relatively thick barricade bar, with the related flanges engaged with the laterally outward surfaces of the barricade bars.

2. In combination, a barricade slab and at least one end support therefor comprising an upright having a transverse straddling foot member, and a pair of clips secured to said upright and located in spaced relation on said upright at an elevated position above said foot member, said barricade slab extending through and embraced by said pair of clips, said clips each comprising a hook element pivotally arranged on an axis substantially parallel to the general transverse direction of said foot member, said hook element comprising a web section accommodating a pivot, at least one arm section in spaced relation to the axial line of said pivot, and jutting transversely from said web section, and an end flange on said arm extending transversely from said arm in a direction away from the axial line of said pivot.

3. A device as in claim 2, said flanged arms being two in number and located on opposite sides of said axial line.

4. A device as in claim 3, said two arms being unequal in length.

5. In combination, a barricade slab and at least one end support therefor comprising an upright having a transverse straddling foot member, and a pair of clips secured to said upright and located in spaced relation on said upright at an elevated position above said foot member, said barricade slab extending through and embraced by said pair of clips, said clips each comprising a hook element pivotally arranged on an axis substantially parallel to the general transverse direction of said foot member, said hook element comprising a web section accommodating a pivot, at least one arm section in spaced relation to the axial line of said pivot, and jutting transversely from said web section, and an end flange on said arm extending transversely from said arm in a direction away from the axial line of said pivot, said flanged arms being two in number and located on opposite sides of said axial line, said two arms being unequal in length, said upright having a plurality of openings for pivoting said hook elements, at least three in number.

6. A device as in claim 5, said upright comprising round stock.

7. A device as in claim 6, said upright comprising tubular stock.

8. A device as in claim 7, said foot member presenting a relatively low silhouette.

9. A device as in claim 8, said upright having a flattened, arcuate section bolted to said foot member, intermediately thereof.
